United States Patent Office.

CALEB CADWELL, OF WAUKEGAN, ILLINOIS.

Letters Patent No. 65,056, dated May 28, 1867.

IMPROVEMENT IN STEAM ENGINES.

The Schedule referred to in these Letters Patent and making part of the same.

TO ALL WHOM IT MAY CONCERN:

Be it known that I, CALEB CADWELL, of Waukegan, in the county of Lake, and the State of Illinois, have invented a new and useful Improvement in Steam Generators; and I do hereby declare that the following is a full, clear, and exact description of the construction and operation of the same, reference being had to the accompanying drawings, and letters of reference marked thereon, making a part of this description, in which—

Figure 1 is a plan view of my generator.

Figure 2, a section taken vertically through fig. 1, showing the cylinder and fire-box.

Figure 3, an elevation of a part of the end of the generator furthest from the cylinder.

Figure 4, an elevation of a portion of the water pipe and pump, with the face plate and the valve of the latter removed.

Figure 5, a perspective representation of the pump-valve and shaft.

The nature of my invention consists, first, in the use of a hollow revolving cylinder placed in the upper part of the fire-box, and arranged to receive a suitable supply of water at one end, and discharge steam into the piston cylinder at the other; second, in the use of a peculiarly arranged pump, consisting of a cylinder made to turn in a suitable metallic stock, and having chambers made in the inner end corresponding with receiving pipes made in the stock, with which said chambers communicate and receive a sufficient supply of water for generating steam in the revolving cylinder; third, thus providing for retaining the heat, and sustaining an even temperature in the fire-box; fourth, the arrangement of a double engine having a vertical central valve operated by a suitable cam or rod for causing steam to press alternately against the opposite ends of the pistons.

By this general construction a steam generator and motive power is provided, which is simple, cheap, and efficient, and can be run with much less fuel than those in common use, as the water strikes the inside of a revolving cylinder, by which means the superheated steam is kept at a more even temperature than when generated in a fixed boiler. And as to the pump, it is constructed to supply the generator without the usual force employed for such a purpose. The whole being arranged with a view of meeting the wants of those desiring a motive power either stationary or portable, which is strong, compact, powerful, and substantial.

In order to give a correct understanding of my device I have marked corresponding parts with the same letters, and will now give a detailed description.

A D, figs. 1 and 2, represent the fire-box, which may be made of iron, or in part of brick. The drawings, however, show the box constructed of iron, and clamped together at B, fig. 2, the top at fig. 1 being removed to show the cylinder C. E F, fig. 1, show the ends of the fire-box, which are made strong enough to support the weight of cylinder C. This cylinder is hung in fire-box A D, at such a point as to make a narrow throat at the top, as seen at fig. 2, for the purpose of concentrating the heat at a place where it is generally the least intense. The cylinder C is hollow, as seen in fig. 2, and has a pipe, G, communicating with hollow bearing H, and cylinder C, fig. 1, for the purpose of conducting water from pump M to the generator C. I also shows a hollow bearing of cylinder C, communicating with steam pipes J K, and piston cylinder L. It will be seen from this description that the hollow bearings H I revolve, while the pipes G J are stationary, and that the joints should be made steam-tight. r r, fig. 1, show holes communicating with openings N N, fig. 4, through which water passes into the chambers P P, fig. 5, of valve 2. Q shows a shaft loosely fitted into the valve 2, in order that the same when worn may adjust itself. And to make the valve 2 turn, a pin is put through the back end of the shaft and fitted into depressions made in the back of the valve, and covered with a suitable packing held in position by means of a bolt or nut. This shaft is made to pass through hole Y, fig. 4, and also through the support Z, fig. 1, which has a suitable opening for allowing a connecting-rod, f, or other suitable device, to be attached to and turn said shaft, a, far enough to empty the water from chambers P into a discharge pipe, not shown in consequence of its being a common arrangement and well understood. It will be seen from this description that the valve 2 has a reciprocating motion, but should the generator require a greater supply of water it can be furnished by giving the valve a rotary motion, in which case only one supply aperture will be required. The cap W, fig. 1, may be made without a recess over the outside of the valve 2, and may have a screw inserted for holding the valve 2 against its seat, or there may be an opening communicating with any

and be led to a suitable discharge pipe to allow the steam to press against the back of the valve and hold it in place. A reservoir or reservoir may be arranged over the openings *r*, fig. 1, through which the steam should be allowed to pass and be discharged into the smoke-stack. The supply of water entering the pump should be regulated by a stop-cock *s* in the pipe leading from the reservoir to the pump. *3* shows a set-screw put through the substantial iron frame and set-screw *4*, and used for and in conjunction with safety-lever *5* in keeping the pipes *G* and *J* steam-tight, and yet allow an over-pressure of steam to escape between pipe *J* and hollow bearing *I*. The above arrangement in pump may be used to inject air into the generator, by making the valve larger, and moving it slowly enough to allow the air to expand before the valve moves past the openings *N N O*, fig. 4. As to the engine, I use a double cylinder, *L*, without heads, having two pistons, operating rods *9* attached to a reciprocating metallic frame *7*, and having a cylindrical valve *6*, figs. 1 and 3, operating between said pistons. The valve *6* is shown more clearly at *B X*, drawing *B*, and is made hollow, and has a partition, *10*, at the centre, as seen in same drawing, and also has the upright elongated openings *11*, for allowing the steam to alternately enter and pass out of the two divisions of the double cylinder *L*. The valve *6* is made to turn and accomplish the above result by means of rod *12*, attached to frame *7*, but may be worked by a cam attached to balance-wheel *S*, fig. 1. The object being to turn the valve *6* from a point as near as possible from the end of the stroke, *13* and *14* represent clamps attached to the cylinder-bed *15*, and used in combination with set-screws *16* and *17* for regulating the valve *6*, and pipe *K* *T* shows cog-wheel which is driven by pinion *U*, rigidly attached to shaft *V*, having suitable bearings in *E* and *F*. It will be seen from this description that wheel *T* causes cylinder *C* to revolve, and shaft *V* to work the pump-valve *2* by means of connecting-rod, *g*. A small pipe may be inserted through opening made for water and air to go in at, the end of which should reach near the surface of the generator *C*, and have a faucet on the outside for drawing off any surplus water which may chance to accumulate. There should be a throttle-valve and a clutch arranged to cut off the steam and stop the machinery, while the generator is allowed to revolve slowly, and not stop while the fire is up. Having thus fully described my device, what I claim, and desire to secure by Letters Patent, is—

1. The double piston cylinder *L*, without heads, and having the valve *6* constructed and arranged with reference thereto substantially as described.

2. The pump-valve *2*, having the shaft *Q* attached and operated as described and set forth.

CALEB CADWELL.
